UNITED STATES PATENT OFFICE.

HENRY C. EGERTON, OF PASSAIC, NEW JERSEY, ASSIGNOR TO WESTERN ELECTRIC COMPANY, INCORPORATED, OF NEW YORK, N. Y., A CORPORATION OF NEW YORK.

TELEPHONIC RECORDING AND REPRODUCING APPARATUS.

1,284,623.

Specification of Letters Patent.

Patented Nov. 12, 1918.

Application filed February 1, 1918. Serial No. 214,906.

To all whom it may concern:

Be it known that I, HENRY C. EGERTON, a citizen of the United States, residing at Passaic, in the county of Passaic, State of New Jersey, have invented certain new and useful Improvements in Telephonic Recording and Reproducing Apparatus, of which the following is a full, clear, concise, and exact description.

10 The present invention relates to electrical recording and reproducing apparatus and more particularly to apparatus to produce a record of matter telephonically transmitted and to telephonically reproduce matter previously recorded.

15 The principal object of the present invention is to provide electrical recording and reproducing apparatus which will accommodate itself to the irregularities and eccentricity of the record so that these will not interfere with uniform and efficient recording upon and reproduction from such a record, and in which the effective mass of the recording or reproducing element resting upon the surface of the record is reduced to a minimum. In accordance with this feature of the invention an electrical recorder or reproducer suitably supported from the traveling carriage of a phonograph to float 20 freely upon the surface of the phonograph record is provided with an armature which, while carrying the recording or reproducing stylus, is mounted for rocking movement relative to the magnet.

25 Referring to the drawing which illustrates an embodiment of the invention applied to telephonic recording and reproducing devices, Figure 1 is a side elevation of a recorder; Fig. 2 is an enlarged vertical cross-section of Fig. 1; Fig. 3, a plan of Fig. 1 with the cover partially broken away; Fig. 4, a perspective on an enlarged scale of the working parts of the recorder shown in Fig. 1; Fig. 5 is an enlarged perspective of an 30 armature carrying a recording stylus; and Fig. 6 is a similar view of an armature carrying a reproducing stylus.

35 Phonographs now in general use are provided with traveling carriages which move the recording or reproducing mechanism along the phonographic record. These carriages usually comprise a supporting member having two openings, in one of which the recording sound box is mounted and in 40 the other of which the reproducing sound

box is mounted. This member is generally pivoted to the traveling mechanism in such a way that it can be readily turned to bring either the recording or reproducing sound box into record engaging position.

45 The accompanying drawings illustrate an embodiment of the present invention as applied to telephonic recorders and reproducers designed to be carried by the supporting member of the traveling carriage of the phonograph in place of the usual recording and reproducing sound boxes. The telephonic recorder and reproducer of the present invention can thus be readily interchanged for the usual recording and reproducing sound boxes and operated with the phonographic apparatus without further change in such apparatus.

50 The telephonic recorder, as shown, comprises a tubular housing 13 designed to fit 75 in the opening 11 of the supporting member 10 of the phonographic apparatus. The housing 13 carries a bracket 14, to the outer end of which a support 15 carrying the working parts of the reproducer is hinged, 80 so as to be freely movable in a direction perpendicular to the direction of cut of the record. The housing 13 has inturned portions 16 and 17 at the top thereof, which are tapped to receive screws 18 and 19. These 85 screws secure a plate 20, preferably of insulation, to the housing 13. The plate 20 carries four binding posts 21 through which the external conductors 22 and 23 are connected to the light flexible conductors 24 and 25 extending to energizing coils 26, and translating coils 27, the conductors 24 and 25 extending through a central opening in the plate 20 provided for this purpose. The coils 26 and 27 surround the outer legs 28 95 and 29 of an E-shaped magnet 30 preferably laminated to minimize eddy current losses. The support 15 is of non-magnetic material and has an upwardly extending portion 31 having a pair of arms 32 integral therewith 100 at the upper end; the arms being substantially parallel and each having right-angled extensions 33 at its upper end which extend toward each other and engage opposite sides of the magnet core 30. An insulating strip 34 carrying a pair of binding clips 35 secured thereto is arranged on the outer side of each of the extensions 33, and a rivet 36 or other suitable fastening device, preferably of non-magnetic material, extends 110

through the strips 34, extensions 33 and core 30 to secure these parts in place and rigidly support the magnetic structure relative to the support 15. The energizing coils 26 are preferably connected in series and have the same direction of wind, the inner end of one and the outer end of the other of these windings being connected to two of the binding clips 35 respectively, which in turn each have one of the flexible conductors 25 secured thereto. The actuating coils 27 are connected to other clips 35 in a similar manner; the direction of wind of the two coils 27 being opposite to each other to vary the magnetic field in accordance with the telephonic currents passing through these actuating coils.

An armature 37 of magnetic material is secured intermediate its ends to a resilient 20 reed member 38, preferably of phosphor bronze, and having a pair of legs 39 integral therewith and bent upwardly to engage the forward ends of the arms 32. Each of the legs 39 has an elongated slot 40, to receive a 25 screw 41, which engages a tapped opening in the respective arms 32 to secure the armature 37 in place, the slots 40 allowing adjustment of the armature 37 relative to the poles of the magnet 30 to obtain the proper 30 air-gap relation therebetween.

The foregoing description applies equally well to telephonic reproducers, the only necessary difference so far as construction is concerned being in the stylus used. In the 35 case of a recorder, a recording stylus 42 is provided to cut sound impressions on the record 43 in response to the armature movements under the action of the telephonic currents traversing the actuating coils 27. 40 The end of the armature 37 of the recorder is also preferably bent as shown in Fig. 5 to present the stylus 42 in a position best adapted to cut the sound impressions on the record 43.

45 In the case of a telephonic reproducer the armature 44 is preferably as shown in Fig. 6, and carries a reproducing stylus 45 to engage the sound impressions of a record to be telephonically reproduced. In reproducing, 50 the engagement of the stylus 45 with the sound impressions of the record effects a mechanical movement of the stylus to vibrate the armature 44, the vibrations of the armature serving in turn to vary the magnetic field of the reproducer. The variations 55 in the magnetic field induce corresponding voice currents in the coils 27, which currents will be impressed upon the telephone line to operate any suitable telephonic receiving device (not shown) connected therewith.

60 The recorders and reproducers are thus formed of a very few number of parts and are of very small mass so that the working parts can ride freely on the record and con- 65 form to any eccentricity of the record with-

out affecting the making of a record or reproduction therefrom as the case may be. The support 15 has an opening 46 therethrough, through which a limiting screw 47 loosely extends; this screw being adjustable 70 in a tapped opening in the bracket 14 and designed to be held in adjusted position by a lock nut 48. The adjustment of the screw 47 is such that the support 15 can move freely within the range necessary for recording or reproducing, as the case may be, but which will prevent the stylus striking against the record arbor or support on removal of the record, as well as hold the recording or reproducing stylus out of contact 75 with the record when the recorder or reproducer, respectively, is moved out of record engaging position.

80 A cover 49 is also provided to fit over the upper part of the housing 13 to inclose the binding posts to prevent tampering therewith and also to protect the working parts against the entrance of dust, the cover 49 having an opening 50 in the top thereof for the passage of the conductors 22 and 23 85 therethrough.

What is claimed is:

1. An acoustic device comprising a member adapted to be secured to a phonograph for movement therewith relative to the phonograph record, a supporting member secured to said first member and movable perpendicularly to the direction of cut of the record, a magnet carried by said supporting member, a coil associated with said magnet, 95 an armature carried by said supporting member and mounted for rocking movement relative to said magnet, and a stylus carried directly by said armature adapted to engage the record. 100

2. An acoustic device comprising a member adapted to be secured to a phonograph for movement therewith relative to the phonograph record, a supporting member secured to said first member and movable perpendicularly to the direction of cut of the record, an electromagnet mounted on and movable with said supporting member, an armature carried by said supporting member and mounted for rocking movement relative to said electromagnet, and a stylus carried directly by said armature adapted to engage the record. 110

3. An acoustic device comprising a member adapted to be secured to a phonograph for movement therewith relative to the phonograph record, a supporting member hinged to said first member and movable perpendicularly to the direction of cut of the record, an E-shaped electromagnet 120 mounted on and movable with said supporting member, an armature secured to and movable with said supporting member and mounted for rocking movement relative to said electromagnet, and a stylus carried di- 125 130

rectly by said armature adapted to engage the record.

4. An acoustic device comprising a member adapted to be secured to a phonograph for movement therewith relative to the phonograph record, a supporting member having a pair of arms and hinged at one end to said first mentioned member for movement perpendicularly to the direction 10 of cut of the record, an electromagnet secured between said arms, an armature carried by said supporting member and mounted for rocking movement relative to said electromagnet, and a stylus carried by said armature adapted to engage the record.

5. An acoustic device comprising a member adapted to be secured to a phonograph for movement therewith relative to the phonograph record, a supporting member of 20 light mass secured to said first mentioned member for movement perpendicularly to the direction of cut of the record, an electromagnet of light mass secured to said supporting member for movement therewith, an armature carried by said supporting member and mounted for rocking movement relative to said electromagnet, and a stylus carried by said armature adapted to engage the record.

30 6. An acoustic device comprising a member adapted to be secured to a phonograph for movement therewith relative to the phonograph record, a supporting member having a pair of arms and secured to said first mentioned member for movement perpendicularly to the direction of cut of the record, an electromagnet secured to said arms for movement therewith, an armature secured to said arms, and capable of rocking 40 movement relative to said electromagnet, and a stylus carried directly by said armature adapted to engage the record.

7. An acoustic device comprising a member adapted to be secured to a phonograph for movement therewith relative to the phonograph record, a supporting member having a pair of arms and secured to said first mentioned member for movement perpendicularly to the direction of cut of the record, 50 an electromagnet secured to said arms for movement therewith, an armature adjustably secured to said arms to vary the air gap between said electromagnet and said armature, said armature being mounted for

rocking movement relative to said electromagnet, and a stylus carried by said armature to engage said record.

8. An acoustic device comprising a member secured to a phonograph for movement therewith relative to the phonograph record, 60 a supporting member hinged to said first mentioned member for movement perpendicularly to the direction of cut of the record and having a pair of arms, an E-shaped electromagnet secured between said arms, an 65 armature, a reed mounting for said armature secured to said arms and supporting said armature for rocking movement relative to said electromagnet, and a stylus mounted on the end of said armature to engage said record.

70 9. An acoustic device comprising a member adapted to be secured to a phonograph for movement therewith relative to the phonograph record, a supporting member hinged 75 to said first mentioned member for movement perpendicularly to the direction of cut of the record and having a pair of arms, an E-shaped magnetic core secured between said arms, an energizing winding to magnetize said core, a translating winding associated with said core, an armature carried by said supporting member and mounted for rocking movement relative to said E-shaped magnetic core, and a stylus carried directly 80 by said armature adapted to engage said record.

85 10. An acoustic device comprising a housing member adapted to be secured to a phonograph for movement therewith relative to the phonograph record, a supporting member secured to said first mentioned member for movement perpendicularly to the direction of cut of the record and having a 90 pair of arms, an electromagnet of light mass 95 secured between said arms, a translating coil associated with said electromagnet, an armature secured to said supporting member and mounted for movement relative to said electromagnet, a stylus carried by said armature to engage said record, binding posts carried by said housing, and flexible conductors connecting said translating winding with said binding posts.

100 In witness whereof, I hereunto subscribe my name this 24th day of January, A. D., 1918.

HENRY C. EGERTON.
